US00D868818S

(12) **United States Design Patent** (10) Patent No.: **US D868,818 S**
(45) Date of Patent: ** Dec. 3, 2019

(54) **DISPLAY SCREEN WITH GRAPHICAL USER INTERFACE FOR LIVE VIDEO SHARING**

(71) Applicant: **Twitter, Inc.**, San Francisco, CA (US)

(72) Inventors: **Tyler Jan Hansen**, San Francisco, CA (US); **Kayvon B. Beykpour**, San Francisco, CA (US); **Joseph Harold Bernstein**, San Francisco, CA (US); **Aaron William Wasserman**, San Francisco, CA (US); **Nils Victor Rocine**, San Francisco, CA (US); **Alexander Kayvon Khoshnevisan**, San Francisco, CA (US); **Geraint John Davies**, Bodorgan (GB)

(73) Assignee: **Twitter, Inc.**, San Francisco, CA (US)

(**) Term: **15 Years**

(21) Appl. No.: **29/674,357**

(22) Filed: **Dec. 20, 2018**

Related U.S. Application Data

(62) Division of application No. 29/589,743, filed on Jan. 4, 2017, now Pat. No. Des. 856,351, which is a division of application No. 29/522,245, filed on Mar. 27, 2015, now Pat. No. Des. 780,785.

CLAIM

The ornamental design for a display screen with graphical user interface for live video sharing, as shown and described.

DESCRIPTION

FIG. 1 is a front view of a display screen with graphical user interface for live video sharing showing a first embodiment; FIG. 2 is a front view of a display screen with graphical user interface for live video sharing showing a second embodiment; and,

FIG. 3 is a front view of a display screen with graphical user interface for live video sharing showing a third embodiment. The broken line showing of a device illustrates environmental structure and forms no part of the claimed design. The broken line showing of portions of the graphical user interface illustrate portions of the article and form no part of the claimed design.

1 Claim, 3 Drawing Sheets
